UNITED STATES PATENT OFFICE.

HENRY STENZ, OF CHICAGO, ILLINOIS.

ELECTRIC-ARC LAMP.

SPECIFICATION forming part of Letters Patent No. 680,082, dated August 6, 1901.

Application filed December 3, 1900. Serial No. 38,385. (No model.)

To all whom it may concern:

Be it known that I, HENRY STENZ, a citizen of the United States of America, residing at Chicago, in the county of Cook and State of Illinois, have invented certain new and useful Improvements in Arc-Lights, of which the following is a specification.

My invention relates to certain improvements in arc-lights, pertaining especially to the means employed for supporting and surrounding the carbons, the objects of the same being to increase the life of the carbons, to render the trimming of the same easier, and to produce a more efficient and satisfactory lamp in other important particulars.

In the drawings, Figure 1 is a side elevation of a complete lamp; Fig. 2, a plan of the globe-cover; Fig. 3, a horizontal section of said cover in line 3 3 of Fig. 4; Fig. 4, an axial section of the globe and lower-carbon support; Fig. 5, a horizontal section of Fig. 4 in line 5 5; Fig. 6, a similar section of the same figure in line 6 6; and Fig. 7, a section corresponding to Fig. 5 of the globe alone, showing a modification in the form of the lower-carbon holder.

Referring to the drawings, A is the frame of the lamp, B the upper-carbon holder, and C a supporting-base. This base is provided with a central vertical opening c, a horizontal annular supporting-plate c', and a surrounding vertical flange c². A preferably three-legged stand D rests, by means of the legs d, upon the annular supporting-plate and is prevented from lateral movement thereupon by the vertical flanges c². Each leg is provided with an adjustable hook d', the point d² of which engages the under surface of the annular plate c', and the upper end of which, d³, is slotted at d⁴ to receive a screw d⁵, by means of which the hook is adjustably clamped to the plate. Means are thus provided for securely fastening the stand D to a wide range of base-plates of whatever thicknesses.

The top of the stand d⁶ is preferably of annular form and provided with two inwardly-extending hooks or lugs d⁷ d⁸, opposite which is a lug d⁹, in which is a threaded screw d¹⁰. The globe E is provided at the bottom with an outwardly-extending flange e, adapted to extend beneath the hooks and the screw and providing means for securely fastening the

globe to the stand. Said globe is preferably provided with a bottom e', closed except a central opening e², through which the carbon 55 may extend and about which is secured a horizontally-projecting flange f of the lower-carbon holder F, and an inner fastening-plate f', secured to said flange by means of screws f². Washers f³, preferably of asbestos, are 60 interposed between the flange and the globe and the plate and the globe to protect the latter from the heat, and also to effect when desired an approximately tight closure. The lower-carbon holder F extends down within 65 the open stand D, preferably in tubular form and is provided at the bottom with a clamping-ring G, having a set-screw g bearing upon the holder itself and drawing the ring tightly against the carbon.

The lower wire H is secured directly to the lower-carbon holder and has no connection with the base or stand, thus removing the necessity for all insulation which has to be used in devices of this sort of the ordinary 75 construction. In this case the insulation is afforded entirely by the bottom of the globe E.

Upon the top of the globe is a hollow cap or cover K, in the bottom k of which are a series of openings k¹ and in the sides another series of openings k², furnishing an indirect passage through the cap for the gases produced within the globe. In the top k³ of the cap is a central opening k⁴, in which is provided a hollow carbon-guide M, perforated 85 at m m' to allow the carbon to pass through and having a horizontal flange m² to rest upon the top of the cover. The cap or cover is centered upon the globe by means of pins k⁵ extending within the globe.

Considerable variation in detail is possible from the exact construction described, and for that reason I do not limit myself to the preferred form herein shown.

I claim as new and desire to secure by Letters Patent—

1. In an electric light, the combination with a suitable supporting-base, C, provided with a horizontal supporting-plate, c', of a stand, D, having legs, d, resting upon the plate, 100 longitudinally-adjustable hooks, d', provided with points, d², embracing the under side of the plate, and slots, d⁴, and screws, d⁵, threaded in the legs and passing through the

slots, whereby the hooks may be adjustable longitudinally to fit the base; substantially as described.

2. The combination with the supporting base, C, of the open stand, D, secured to the base, the globe, E, secured to the stand and provided with the bottom, e', and the carbon-holder, F, secured to said bottom and extending downward within the open stand; substantially as described.

3. The combination with a hollow cap or cover, K, provided with perforations, k^1 , k^2 , and the central opening, k^4 , in the top, of the hollow carbon-guide, M, having the flange,

m^2 , and the perforations, m , m' , to receive 15 the carbon, the body of the guide projecting downward into the opening, k^4 , and the flange, m^2 , resting upon the top of the cover; substantially as described.

In witness whereof I have hereunto set my hand, at Chicago, in the county of Cook and State of Illinois, this 8th day of November, A. D. 1900.

HENRY STENZ.
